UNITED STATES PATENT OFFICE.

JOHN L. STROW AND CLARENCE D. STROW, OF FORT DODGE, IOWA.

DESIGN FOR A PUZZLE-BOARD.

SPECIFICATION forming part of Design No. 32,890, dated June 26, 1900.

Application filed May 24, 1900. Serial No. 17,889. Term of patent 34 years.

To all whom it may concern:

Be it known that we, JOHN L. STROW and CLARENCE D. STROW, citizens of the United States, residing at Fort Dodge, in the county 5 of Webster and State of Iowa, have invented and produced a new and original Design for a Puzzle-Board, of which the following is a specification.

The invention relates to a new and original design for a puzzle-board; and it has for its object to provide a design of this character which will be both useful and ornamental.

The essential feature of the design resides in a body or board having a circular recess 15 with a central raised or convex portion and a series of approximately U-shaped stalls spaced from the center of the recess and opening toward the same.

In the drawings, Figure 1 is a perspective 20 view of a puzzle-board, showing our new and original design. Fig. 2 is a sectional view of the same.

Referring to the drawings, 1 designates a rectangular body or board provided with a 25 circular depression or recess 2 and having a

central circular raised portion or convexity 3, gradually tapering toward the walls of the recess and presenting an exterior inclined or sloping surface. Arranged around the center of the recess, on the inclined faces of the 30 raised or convex portion, is a series of stalls or pens 4, which are approximately U-shaped and which have their openings or entrances at their inner ends and facing the center of the recess. The upper edges of the approximately 35 U-shaped pens or stalls are horizontal and are arranged in the same horizontal plane as the upper surface of the outer marginal portion of the rectangular body or board.

What is claimed is—

The design for a puzzle-board herein shown and described, substantially as set forth.

In testimony that we claim the foregoing as our own we have hereto affixed our signatures in the presence of two witnesses.

JOHN L. STROW.
CLARENCE D. STROW.
